UNITED STATES PATENT OFFICE.

JOHN M. MOTT, OF CHICAGO, ILLINOIS.

IMPROVEMENT IN LIGHTNING-RODS.

Specification forming part of Letters Patent No. 127,094, dated May 21, 1872.

To all whom it may concern:

Be it known that I, JOHN M. MOTT, of the city of Chicago, in the county of Cook and State of Illinois, have invented a new and valuable Improvement in Lightning-Rods; and I do hereby declare that the following is a full, clear, and exact description of the construction and operation of the same, reference being had to the annexed drawing making a part of this specification, and to the letters and figures of reference marked thereon.

Figure 1 of the drawing is a representation of an end view or cross-section of the rod before it is twisted. Fig. 2 is a cross-section of the rod after it has been twisted together and completed. Fig. 3 is a side view of the twisted rod.

My invention has relation to lightning-rods; and consists in constructing such rods with wires of galvanized iron and a central plate of copper and twisting the same together, as hereinafter specified and claimed.

A of the drawing represents a plate of copper, which constitutes what I denominate the central plate of my lightning-rod; and the letters C represent wires of galvanized iron.

In constructing my lightning-rod I place the wires C on each side of the plate, as shown on Fig. 1, and then twist them all together. When this is accomplished it assumes the form shown on Fig. 3.

I am aware that lightning-rods have heretofore been constructed by L. J. Hawley, and mentioned in his patent of February 2, 1866, with a central plate of copper supported between solid semi-cylindrical bars of iron; and I therefore lay no claim to such invention; but

What I claim as my invention is—

The lightning-rod herein described, constructed with central copper plate A and galvanized wire C twisted together, substantially as specified.

In testimony that I claim the above I have hereunto subscribed my name in the presence of two witnesses.

JOHN M. MOTT.
